VEHICLE DOOR LATCH

Burnie J. Craig, Los Angeles, Calif.

Application September 18, 1950, Serial No. 185,411

11 Claims. (Cl. 70—285)

1

This invention relates to a vehicle door latch. The general object of the invention is to provide an improved vehicle door latch including novel lock means for controlling operation of the latch on a door of an automotive vehicle.

A more specific object of the invention is to provide a door locking system including novel means for unlocking and/or locking a plurality of the doors of an automotive vehicle and wherein speed responsive means controls the operation of the release means for the latches which hold the doors closed.

Another object of the invention is to provide door latching means including a novel lock means which is operable in a novel manner to unlock the latch.

Another object of the invention is to provide a novel door latch handle assembly.

Another object of the invention is to provide a novel combined key-controlled and dial actuated tumbler controlled lock assembly.

Another object of the invention is to provide a novel push button operated latch release member and latch lock.

Another object of the invention is to provide a novel push button latch release member including a novel keyless actuated unlocking member.

A further object of the invention is to provide a latch locking means wherein a push button actuated key lock member is provided and wherein a dial actuated tumbler lock device is mounted coaxial with the push button member.

A further object of the invention is to provide a vehicle door latch handle assembly which carries push button means for operating a door latch to release position and wherein a plurality of independently operated means is carried by the handle for unlocking the latch to render the push button means operative to open the door.

Another object of the invention is to provide a door latch including latch releasing means and locking means operable when the latch is in locked position and the door is shut to cause the latch to be unlocked or, by manipulation of a manual member, to remain locked, depending upon the position of the manual member when the door is closed and wherein a keyless lock is employed to unlock the latch.

Another object of the invention is to provide a vehicle door latch including a novel locking member which is movable from locked to unlocked positions and which includes a novel latch releasing member which is controlled by novel lock means and is movable to release the door

2

latch when the locking member is in one position and is ineffective to release the latch when moved by the locking member which is in another position.

5 Other objects and advantages of the invention will be apparent from the following description taken in connection with the drawings, wherein:

Fig. 1 is a fragmentary side elevation showing an automotive vehicle equipped with the present invention;

Fig. 2 is an enlarged, sectional view taken on line 2—2, Fig. 1;

Fig. 3 is a sectional view taken on line 3—3, Fig. 2;

15 Fig. 4 is a fragmentary front view showing the door pillar and strike;

Fig. 5 is an enlarged central sectional view showing the latch operating parts;

Fig. 6 is a section taken on line 6—6, Fig. 5;

Fig. 7 is a section taken on line 7—7, Fig. 5;

Fig. 8 is a central sectional view showing the parts in a different position from that shown in Fig. 5;

Fig. 9 is a view similar to Fig. 5, showing the parts in still another position;

Fig. 10 is a fragmentary elevation corresponding to line 10—10, Fig. 8, showing the push button operated actuating member;

Fig. 11 is a perspective view showing the coincidental locking and speed controlled mechanism;

Fig. 12 is a front end view of the pillar lock barrel, and

Fig. 13 is a fragmentary view similar to Fig. 5, showing a modification.

Referring to the drawing by reference characters, the invention is shown as embodied in door latches arranged upon doors A of a multi-door vehicle B.

40 As shown, each latch includes a base plate 10, having a flange 11 thereon which is provided with a slot 12 through which a pivoted bolt 13 protrudes. The bolt 13 is shown as pivotally mounted on the base plate at 14 and at its outer end supports a strike engaging roller 15.

The latches in the present disclosure are of the type shown in applicant's copending application Serial No. 103,431, filed July 7, 1949, now Patent No. 2,659,230, issued November 17, 1953.

45 The protruding roller 15 moves in an inclined slot 16 in a strike member 17, arranged upon the car pillar 18. The slot 16 is inclined so that as each door closes its associated roller moves from one end of the slot 16 towards the other end to 55 fully engaged position behind the portion 19 of

the slot. To hold the bolt in this position and thereby hold the door closed, a catch member 20 is pivotally supported at 21 upon the base 10, and includes notched portions 22 and 23.

The bolt 13 includes an outwardly directed pin 24 which rests upon the notched portion 22 when the bolt is in the disengaged position. When the bolt is moved to safety latched position, the pin engages the notch 23 and when the bolt is raised to fully engaged position (see Fig. 3), the bolt engages the notched portion 25, just above the notch 23. When so engaged the bolt cannot move downwardly to disengaged position until the catch member 20 is swung about its pivot 21 and is released, as will be hereinafter described. A tongue 25' on the base plate limits movement of the catch member in one direction.

One end of a spring 26, arranged about the pivot pin 14, engages a pin 27 on the catch 20 and urges the catch 20 to bolt holding position while the other end of the spring 26 engages a pin 28 on the bolt 13 to normally urge the bolt downwardly to disengaged position.

The bolt may be released by means of an inside remote control door handle 29 which includes an arm 30, disposed inside the door and adapted to be rocked by the handle 29. The arm 30 is connected to one end of a rod 31, the other end of the rod fitting in a hole 32 in a rock arm 33 which is mounted on the pivot 21. The lower end of the rock arm engages an actuating pin 34 mounted on a latch releasing member 35. The rock arm will thus move the pin 34 and the pin will move the catch 20, thus permitting the spring 26 to move the latch bolt to disengaged position as the door is opened.

In order to provide means exterior of the vehicle for releasing the catch members 20 and also to provide means for locking the release means against unwarranted operation, a carriage member 36 is provided for each latch releasing arm. Each carriage member is pivoted on a pivot 37 on the base 10. One end of the carriage member 36 is raised as at 36' and a snap-over spring 36'' is arranged between this raised portion 36' and the base 10 to hold the carriage member in either one of its two positions. Tongues 35', struck from the base 10, limit movement of the carriage member 36.

The carriage member 36 includes a projecting end portion 38 which extends through a slot 38' in the flange 11. The end of the portion 38 is formed into a cylindrical shape to support a roller 38''.

The carriage member is similar in some respects in construction and operation to the carriage member shown in Fig. 32 of the applicant's prior Patent No. 2,204,208, granted June 11, 1940.

Guide tongues 39 on the carriage member 36 slidably support the latch release member 35 previously mentioned. When the carriage member is in the position shown in Fig. 3 and the release member 35 is moved, the pin 34 will engage the tongue 40 on the catch 20 to move the catch. A tongue 41 on the carriage member limits movement of the release member in one direction.

When the carriage member 36 is swung about its pivot 37, the pin 34 will be disposed opposite a slot 40' in the catch 20 so that when the release member 35 moves to releasing position, the pin 34 will move into the slot 40' without moving the catch member 20. The latch just described is disclosed in the applicant's patent No. 2,659,230 mentioned above.

The carriage member 36 includes an elongated

slot 46 (see Fig. 8), which is aligned with a slot 47 in the base 10, and the latch releasing member 35 is also provided with a slot 48, aligned with the slots 46 and 47. The slots 46, 47 and 48 receive one end portion of a bell crank releasing arm 49, which may be operated from the exterior of the door, as will be described.

The released arm 49 is shown as pivoted at 50 to ears 51 struck from the base 10. One portion of the bell crank 49 engages one end wall of the slot 48. The other portion 52 of the bell crank is provided with a slot 52a. An actuating member 53 is carried by an outside actuator indicated generally at 54. The member 53 carries an integral tongue 53' which engages the slotted portion 52a of the bell crank to rock the latter. The outside actuator is similar in some respects to the handle assembly disclosed in applicant's prior patent 2,450,372, granted September 28, 1948, and is also similar to the outside actuator disclosed in applicant's Patent No. 2,659,230, mentioned above.

As shown, the outside actuator 54 includes a body 55 which has a handle grip member 56 thereon. The body 55 may be held in place by means of a slip plate 58 which engages in notches 57 in the body.

The body 55 has a bore 59 and at the outer end has an enlarged bore 60. At the inner end the body 55 is open to receive a closure 61 which is held in place against rotation by a tight fit and by a split ring 62. The closure 61 supports a sleeve 63 which has spaced tongues 64 thereon which pass through slots 65 in the closure 61 and are bent over to hold the sleeve in place.

About the sleeve 63 I arrange a dial member 66 which has a finger engaging head portion 67 and a tubular body 68. The dial member rotates about the sleeve 63 and in the bore 60 and is slideable in the bore 60. The dial member is also slideable upon the sleeve 63 and at its inner end is cut away as at 69 to provide an annular recess in which a spring 70 is arranged. The spring 70 bears against the closure 61 and normally urges the dial member outwardly.

The closure 61 includes an inwardly directed flange 61' which is fitted in the enlarged portion 60 of the body 55.

Upon the dial member I arrange a series of tumblers, shown as three in number, 71, 72 and 73, which are free to rotate about the dial member and are provided with the usual tumbler pins 74. Tumbler locks of this type are common and well known and a further description thereof is believed unnecessary. The tumbler 73 is provided with a slot 75 which receives a key 76 on the dial body 68 and the construction is such that after the tumblers have been set and as the dial moves inwardly, tensioning the spring 70, the key 76 will move in the slot 75.

The tumblers 71, 72 and 73 are shown as spaced apart by collars 77 which are annular and integral with the tumblers. In operating the dial the key 76 will cause the tumbler 73 to first rotate, whereupon the pins on this tumbler will rotate the tumbler 72 and the pins of tumbler 72 will rotate the tumbler 71.

The dial member body 68 is provided with a plurality of ears 80, with one ear for each of the tumblers 71, 72 and 73, and the tumblers are provided with notches or gates 81, which when the tumblers are correctly aligned each receives a companion ear 80. The construction is such that when the head portion 67 of the dial member 66 is rotated the tumblers, when the correct positioning has taken place, will be aligned, with each

of the slots 81 aligned with its companion ear 80, whereupon the dial head 67 may be pushed inwardly until the end 82 of the dial body engages the closure 61.

The sleeve 63 slidably receives a lock barrel 85. This lock barrel includes a body 86 and a push button end 87. The push button end extends through a hole 83 in the dial head 67. The details of the key lock form no part of the present invention as such locks are common and in well known use.

The construction is such that when a key 88 is inserted in the barrel 87 and rotated, suitable pins (not shown) will be aligned, permitting the key to turn the push member relative to the lock barrel in either direction from a normal position. The turning of the key rotates a head member 89 on the push member and rotates a head member 89 on the push member and rotates the releasing arm 53 which is carried by the head member and was previously mentioned. The releasing arm 53 and tongue 53' swing only through a small angle when moved and at all times contact the bell crank arm 52 so that they may rock the latter. Shoulders 91 and 92 on the barrel 85 and the sleeve 63 limit outer movement of the lock barrel. A spring 93 normally urges the lock barrel outwardly.

In order to prevent rotation between the sleeve 63 and the barrel 85 a clutch device, which includes a ball 100, is provided. This clutch ball is arranged in a slot 101 in the sleeve 63 and the ball in normal position also is engaged in a substantially hemispherical seat 102 in the barrel 85. The slot 101 is of sufficient width to receive the ball but does not permit circumferential movement of the ball about the axis of the dial. The slot 101 is elongated as shown in Fig. 5 so that the rotary movement of the barrel is normally prevented while axial movement is permitted.

When in this position the push button may be operated to cause inward movement of the releasing arm 53 to thereby rock the bell crank member 52 to cause the end 49 thereof to move the release member 40 to release the bolt, or the key 88 may be inserted and the lock barrel may be rotated, thus turning the head member 89 clockwise or counterclockwise and causing the inner end of the member 53 to rotate about the axis of the lock barrel to thus cause the locking arm 36 to be raised or lowered.

The lock barrel is keyed by the clutch ball 100 to the sleeve 63 so that relative rotation between the lock barrel and the sleeve is prevented.

With the construction heretofore described, a person without a key could not rotate the lock barrel and operating member 53 to move the carriage member to unlocked position. The following mechanism provides for this unlocking without use of a key.

The dial member 67 has an arcuate, elongated recess 103 which, after the tumblers have been aligned and the dial head 67 pushed inwardly, will become aligned with the clutch ball to permit the clutch ball to move from the semi-spherical recess 102 into the arcuate recess 103. In this position there may be limited rotary movement between the sleeve 63 and the lock barrel 85. The slot 103 being circumferentially elongated, once 70 the ball 102 enters the slot 103 there may be limited rotary motion of the dial head 67.

When the dial head is pushed in after it has been correctly aligned, a slot 105 on the dial head will be engaged by a key 106 on the push member 75

87 so that thereafter when the dial is rotated the push member and lock barrel will be rotated and rotation of the push member will give this member the same motion as when rotated by a key 5 so that the push member may rotate the arm 53 to operate the carriage member 36 from locked to unlocked position or vice versa.

In order to prevent a vehicle operator from locking himself out of the vehicle through inadvertently closing the door when the locking member 36 is in locked position, the catch member 20 is provided with a restoring pin 110 which is disposed adjacent to, and is adapted to engage, the lower edge 111 of the catch releasing member 35. The pin 110 is disposed at one side of the axis of the pivot 37 and the construction is such that when the catch member 20 is rocked by the spring 26 as the door is closed, the pin 110 will shift with the catch member 20. Thus when the carriage member 36 is in locked position and the member 20 is rocked in the act of closing the door, the pin 110 will move upwardly slightly and will engage the edge 111 of the latch releasing member 35 and will rock the member 35 upwardly. The member 35 is carried on the carriage member 36 and the arrangement of parts is such that the carriage member 36 will be moved to unlocked position, where it will be held by the spring 38'. Thus the likelihood of any operator locking himself out of the vehicle due to thoughtless closing of the door when the latch is locked will be prevented.

However, should the operator desire to lock the vehicle door without the use of a key, he may operate a push rod 112 on a door, moving the carriage member 36 on that door to locked position whereupon the operator will press the push button 87 on the same door and in doing this will move the latch releasing member 35 so that the pin 110 will be moved from the edge 111 and will be aligned with a slot 113 in the latch releasing member 36. Thus when the door is closed and the catch member 20 moves the pin 110 will pass into the slot 113 and will not engage the edge 111 and therefore the carriage member 36 will remain locked.

Thus by dual manipulation—that is by pushing on the push member 87 and at the same time closing the door when the carriage member 36 is in locking position, the operator will cause the parts to remain locked. Further, as hereinafter explained, due to a coincidental locking system to be later described, this dual act will also cause all of the other doors besides the one door being closed to be locked regardless of whether the other doors were in locked or unlocked position when the one door was closed.

The latches described above may be used individually as single latches. They may also be used with a coincidental locking device and/or with a vehicle speed control for releasing the latches, as will be later described.

For coincidental locking the rollers 38' on the lock members 34 of adjacent door latches are adapted to move into substantially U-shaped wings 120 (see Fig. 11), mounted at the two ends of a locking bar 121 which has a lever 122 connected thereto. The bar 121 includes arms 123 which are pivoted as at 124 to uprights 125 struck from a base 126 of a speed control and lock assembly 126'. The uprights 125 are supported by braces 125' bent up from the base 126. This assembly also includes a vertical portion 127 which supports the barrel 128 of a key operated lock, the operating details of which form no part of the

present invention. The lock 128 includes a projecting cylindrical member 129 which has a crank 130 mounted thereon and the crank 130 includes a crank pin 131 which fits in the slot 136 in the locking bar 121.

The lock is adapted to be turned by a suitable key from a neutral position in either direction. This turning of the lock moves the crank 130 from an upper position to a lower position, and vice-versa, and in so doing the pin 131 moving 10 in the slot 132 in the locking bar 121 raises and lowers the bar 121 and thus raises and lowers the wings 120.

The lever 122 on one side of the vehicle is connected by a Bowden wire 133 with a similar lever 122 on the other side of the vehicle, with the Bowden wire preferably passing beneath the vehicle body. The Bowden wires are so connected to the levers that when the lever on one side is depressed or raised the lever on the other side of the vehicle will be also depressed or raised.

The speed control and lock assembly may be suitably secured on the vehicle body in a position wherein the wings 120 are disposed to receive the rollers 38" when each door is closed. A snap-over spring 135 holds the bar 121 and wings 120' in either up or down position after they have been moved to such position. Stops 36 limit the movement of the bar 121.

When two adjacent doors are closed and the rollers 38" are in the wings 120 with the locking bar 121 in the position shown in Fig. 11, the carriage members 36 will be in a position to cause the associated latches to be unlocked. When, under this condition, a key is inserted in the lock 128 and the lock 128 is moved to locked position, that is, the lock is moved so that the pin 131 is lowered and the locking bar 121 is moved downwardly, the wings 120 will move downwardly and thus will move the rollers 38" and will move the associated carriage members 36 downwardly so that the latter will be in locked position.

The slot 132 is of a shape to permit the pin 131 to move up and down therein. The lock 128 is preferably of the well known character wherein a key must be turned to a normal intermediate position before the key can be removed. When the pin is in this normal position and the wings 120 are in unlocked position the pin will be adjacent to the lower face of the slot 132 and when the wings 120 are in the reverse position the pin will be adjacent to the upper edge of the slot. This allows the wings 120 to be moved to locked and to unlocked position by the lever 122 independent of the position of the pin 131.

As the wings 120 move about the pivot 124 from locked to unlocked position, there is a slight forward and backward movement of the wings relative to the face 127. The wing support, however, is slightly flexible and loosely fitted together so that this slight movement of the wings 120 does not cause a binding action due to the rollers 38" pressing against the wings.

When any key 88 of a latch is turned from locked to unlocked position or vice-versa, the releasing arm will be rocked about the axis of the push member 87 and will be swung upwardly or downwardly. The member 53 must be in normal intermediate position when the key is removed and when in this position the releasing arm 53 will fit in the slot 46 as shown in Fig. 3 when the device is unlocked. The slot 46 is shaped to permit the releasing arm to fit therein in reverse position when the latch is locked.

By rotating the key 62 or by correctly position-

ing the tumblers and pushing in on and rotating the dial head 67, it will be seen that the releasing arm 53 will be rocked about its axis (which coincides with the axis of the push member 87) and will raise the locking member 36 upwardly or downwardly, depending upon the direction of movement of the releasing arm. This upward or downward movement of the releasing arm will cause similar movement of the members 35 and 36 and will likewise shift the rollers 38" upwardly or downwardly and thereby shift the wings 120 in a similar direction and manner.

Thus it will be apparent that all the latches on closed doors can be coincidentally locked or unlocked either by operating the key in the lock member 128 or by operating the key 88 in any one door handle or by operating the keyless dial head 67, and that all the latches may be locked by pushing down any locking member 112 or by rocking the lever 122.

Each speed control and lock assembly 126' vertical portion 127 has a tongue 140 extending at right angles thereto and this tongue includes a downwardly bent end 141 which carries a pivot pin 142 which supports a downwardly depending, generally U-shaped spring 143. The spring includes a pair of opposed vertical portions 144 from which opposed inclined tabs 145 extend. The spring includes downwardly converging portions 145 which terminate in short vertical tongues 146 which normally are slightly spaced apart by the resiliency of the spring material. A solenoid 147 on the base 126 has an armature 148 which has a rounded end 149 which, when the solenoid is energized, moves between the tongues 146.

To energize the solenoid 148 one lead 150 therefrom is shown as passing to a contact 151 on an arcuate circuit closer 152. The other lead 153 extends through a source of current 154 to the needle 155 of a vehicle driven speedometer 156 and the construction is such that when the speedometer needle 155 is moved when the vehicle goes into motion this needle will close the circuit from the lead 150 to 153 and thus will energize the solenoid and cause the armature to move upwardly against the tension of a spring (not shown). When the vehicle speed decreases to a predetermined rate, the solenoid will be de-energized and the armature 148 will move from between the tongues 146 of the spring 143. The spring 143 is of such character that normally the vertical portion 144 may be moved inwardly easily when the solenoid is not energized.

The latch releasing member extensions previously mentioned are in the nature of speed controlled feelers and each of these extensions has its free end adjacent to the vertical portion 144 of the spring. Thus when the latch releasing member starts its movement towards latch releasing position the associated extension 41 will engage the spring portion 144 (see Fig. 8). When the solenoid is not energized the spring will bend easily and thus there will be no resistance to the operation of the latch releasing member. When, however, the solenoid is energized and the solenoid armature 148 is between the tongues 146, the spring can be flexed only under great force and at this time will require great pressure to move the latch releasing member to latch releasing position.

Thus it will be seen that when the vehicle is at rest the latches may be released from within or from without the vehicle to open the doors with only a light finger tip pressure. However, when

the vehicle is moving above a predetermined rate of speed the latch releasing members can only be operated with difficulty. Thus accidental door opening is prevented while at the same time the fear of riders who object to riding in a vehicle the doors of which are locked against opening is overcome.

The speed controlled and coincidental locking mechanism is like that described in the applicant's prior application Serial No. 103,431, mentioned above.

To open the doors from without pressure on the push member 54 will rock the releasing arm 49 and will cause the associated latch releasing member to be moved by the arm 49 to releasing position. If the locking mechanism is in locked condition, movement of the arm 49 will merely cause the latch releasing member to move idly since in that position the pin 34 will move into the notch 40'.

In closing the door when all of the latches are unlocked and the carriage member 36 is in unlocked position with the parts as shown in Fig. 2, the operator merely closes the door and the parts remain in the condition shown in Fig. 2. When in this condition, from within the vehicle, all doors may be locked by pushing on any one push rod 112 or by rocking the lever 122 to locked position. From without the vehicle all doors may be locked by operating the key 88 or the key for the lock 128 to locked position. All doors may be unlocked when they are locked by reversal of the operations just described.

In operation—and assuming that all doors are closed and that the vehicle is at rest—the operator may turn any remote control handle 29, thus causing the rod 31 to rock the catch member 20 and thus free the associated bolt. When the bolt is freed, opening of the door causes the roller 15 to move along the groove 16 and then to pass from this groove.

If the vehicle is at rest when the above operation takes place, the extension 41 on the latch release member will engage the associated vertical portion 104 of the spring and will push that portion without difficulty.

When the vehicle is running and the solenoid armature 148 is disposed between the tongues 146 the force required to move the portion 144 of the associated spring will be such that the operator 29 can be actuated only with great difficulty. Thus accidental opening of the door is prevented.

Full movement of the actuating member 53 by the push button will not move the pin 34 enough to engage the rear wall of the slot 40' so that no unlocking occurs. However, when the operator 29 is turned it will move the member 33 far enough to shift the pin 34 against the rear wall of the slot 40' and thus rock the member 20 and release the latch.

The above described operation of opening any door from within by operating the remote control handle 29 applies regardless of whether or not the latches are in locked or unlocked condition.

Assuming now that certain of the doors are closed and that the locking mechanism for the closed doors is in locked condition: If the operator now closes another door, the carriage member 36 of which is in unlocked condition, this will cause the roller 38'' on the one door to move its associated wing 120, thus causing all of the wings to move to unlocked position.

This is done by the roller 38'' camming against the adjacent portion of the wing 120. This occurs while the catch member 20 is being rocked by the

pin 24 passing from notch 22 to notch 23 and to edge 25 so that the pin holds the carriage member 36 in the position shown in Fig. 3 and thus overcomes the tension of the springs 36'' and 135 which tend to hold the doors previously locked in that condition.

Assuming now that certain of the doors are closed and that the locking mechanism for the closed doors is in unlocked condition and that the operator wishes to cause all of the doors to be locked: The operator will press down on the push rod 112 on the door which is being closed, this will place the carriage member 36 of the door being closed in locked condition. The operator will thereupon press the push member 87 inwardly and will at the same time close the door. In this position movement of the catch member 20, by its engagement with the pin 24 on the bolt, will take place with the pin 110 on the catch member passing into the slot 113 and the pin 34 will be disposed in the notch 40'. In this condition the roller 38'' will enter its associated wing 120. The pin 34 will then engage the lower edge of the notch 40', thus preventing the carriage member 36 from shifting to unlocking position, and the roller 38'' will thus pass into its associated wing and will pull this wing from unlocked condition to locked condition and will cause all of the other wings to move to locked condition.

When any door is closed with the push member 87 moved inwardly as in the operation described in the preceding paragraph, the extension 41 will be advanced and as the door closes will strike an inclined tab 143' on the spring 143 and as it moves along the tab will push the portion 144 of the spring inwardly so that the parts assume the position shown in Fig. 3. The spring will offer no substantial resistance to this movement when the vehicle is at rest but should a door be closed while a vehicle is in motion so that the solenoid armature end is between the ends 146 of the spring, an added force must be applied to the door to close the same.

Assuming now that certain of the doors are closed and are unlocked and that the operator closes one door which, unknown to him, has been placed in locked position, then in this circumstance when the operator closes this one door without pressing on the associated push member 87, the one door will become unlocked and the others will remain unlocked.

In Fig. 13 a modification is shown. In this figure parts similar to those previously described are designated by primed reference numerals.

In the modification the slot 105 on the dial head and the key 106 on the push member 87' have been omitted. Otherwise there are no changes. In operating the modification the dial is rotated to correctly align the tumblers and thereafter the dial is pushed inwardly to cause the ball 100' to be aligned with the recess 103'. The push button 87' is then free to turn and as it turns it will swing the head member 89' thus causing the actuating member to move to unlock position.

It will be understood that under certain installations the lock 128 on the pillars may be omitted and only the key operated locks may be employed. Also, under other conditions, it may be desirable to omit the locks 85 operated by the key 88 and make the members 54 merely push members and depend only on the locks 128 as the key operated members.

From the foregoing description it will be apparent that the present disclosure relates to a

11

novel latch construction which, if desired, may include coincidental locking mechanism and/or safety release controls and wherein the parts act in effective manner to perform their intended functions.

Having thus described my invention, I claim:

1. In a vehicle door latch assembly which includes a bolt, a locking member for the bolt, and an actuating member for moving the locking member to unlocked position, a fixed support, a lock barrel movably mounted to rotate and to reciprocate on the support, clutch means normally holding the lock barrel against rotation relative to the support while permitting reciprocation thereof, and tumbler controlled means to free the clutch means and to permit rotation of the lock barrel, the actuating member being mounted on the lock barrel and movable axially to free the bolt, said actuating member being moved when the lock barrel is rotated to move the locking member to unlocked position.

2. In a vehicle door latch assembly which includes a bolt, a locking member for the bolt, and an actuating member for moving the locking member to unlocked position, a fixed support, a push button lock barrel movably mounted to rotate and to reciprocate on the support, means to normally hold the lock barrel against rotation relative to the support while permitting reciprocation thereof, said actuating member being mounted on the lock barrel and movable axially to free the bolt when the latch is unlocked, said actuating member being movable when the lock barrel is rotated and adapted to move the locking member to unlocked position, and tumbler controlled means operable to free the holding means and to permit rotation of the lock barrel and actuating member.

3. In a vehicle door latch assembly which includes a bolt, a locking member for the bolt, and an actuating member for moving the locking member to unlocked position, a fixed support, a lock barrel rotatable on the support, means to normally hold the lock barrel against rotation relative to the support, a head member within the lock barrel, key controlled means for normally preventing relative rotation between the head member and lock barrel, the insertion of a key in the head member permitting rotation of the head member relative to the lock barrel, tumbler controlled means to free the holding means to permit rotation of the head member and lock barrel as a unit, and a lock actuating member carried by the head member and movable when the head member is rotated and adapted to move a locking member to unlocked position.

4. In a vehicle door lock, a fixed support, a bolt, a push button lock barrel movably mounted to rotate and to reciprocate on the support, means to normally hold the lock barrel against rotation relative to the support while permitting reciprocation thereof, a head member within the lock barrel, key controlled means for normally preventing relative rotation between the head member and lock barrel, the insertion of a key in the head member permitting rotation of the head member relative to the lock barrel, tumbler controlled means to free the holding means to permit rotation of the head member and lock barrel as a unit, and an actuating member carried by the head member and movable axially to free the bolt when the lock is unlocked and rotatably movable when the head member is rotated

12

and adapted to move a locking member to unlocked position.

5. In a door handle assembly, a body having a chamber therein and having a bore communicating with the chamber, a cylindrical dial body rotatable in said bore, a dial head carried by said body, gated tumblers rotatable in said body, said dial head projecting beyond the bore for engagement with the finger of an operator to permit rotation of said tumblers, means permitting inward movement of the dial head when the tumblers are correctly positioned, a sleeve fixed within said chamber and disposed within said dial body, a lock barrel slidable in and rotatable in said sleeve, said dial head having a bore therein, said lock barrel including a push button extending through said bore, a head member rotatably mounted in said lock barrel, clutch means normally preventing relative rotation between the lock barrel and sleeve, key released means normally preventing rotation of the head member in the lock barrel, an actuating member carried by the head member, said clutch means being operable to free the lock barrel from the sleeve when the dial body is pushed inwardly.

6. In a door handle assembly, a body having a chamber therein and having a bore communicating with the chamber, a cylindrical dial body rotatable in said bore, a dial head carried by said body, gated tumblers rotatable in said body, said tumblers having pins thereon, a fixed closure for said chamber, said dial head projecting beyond the bore for engagement with the finger of an operator to permit rotation of said tumblers, means permitting inward movement of the dial head when the tumblers are correctly positioned, a sleeve carried by said closure and disposed within said dial body, a lock barrel slidable in and rotatable in said sleeve, means normally urging said lock barrel outwardly, said dial head having a bore therein, said lock barrel including a push button extending through said bore, a head member rotatably mounted in said lock barrel, clutch means normally preventing relative rotation between the lock barrel and sleeve, key released means normally preventing rotation of the head member in the lock barrel, an actuating member carried by the head member, means to free the lock barrel from the sleeve when the dial body is pushed inwardly, and means clutching the dial body to the lock barrel when the dial body is pushed inwardly.

7. In an automotive vehicle door latch, a base plate, a bolt movable on the base plate to engaged and released positions, means holding the bolt in engaged position, means to release the bolt holding means, said release means including a pivoted carriage, a reciprocatingly mounted control member on the carriage, means to releasably hold the carriage in each of the two positions, means to release the bolt when the control member is moved in one direction while the carriage is turned to one position about its pivot, the last means being ineffective to release the bolt when the control member is similarly moved while the carriage is turned to the other position about its pivot, a lock support, means to normally hold the support against rotation, a lock barrel rotatable in the support, means to normally hold the lock barrel on the support against rotation relative thereto, a head member within the lock barrel, key controlled means for normally preventing relative rotation between the head member and lock barrel, the in-

sertion of a key in the head member permitting rotation of the head member relative to the lock barrel, gated tumbler controlled means to free the holding means to permit rotation of the head member and lock barrel as a unit, and a lock actuating member carried by the head member and movable when the head member is rotated for moving the carriage to unlocked position.

8. In a door handle assembly, a body having a chamber therein and having a bore communicating with the chamber, a cylindrical dial body rotatable in said bore, a dial head carried by said dial body, tumblers rotatable on said dial body, means whereby the dial body rotates the tumblers, a fixed closure for said chamber, each tumbler having a notch in its periphery, said dial body having spaced tongues disposed to enter said notches when the tumblers are correctly positioned, said dial head projecting beyond the bore for engagement with the finger of an operator to permit rotation of said dial body, a sleeve within said dial body, means to prevent rotation of the sleeve, a lock barrel slideable within said sleeve, means normally urging said lock barrel outwardly in the sleeve, means to limit the outward movement of the lock barrel, said dial head having a bore therein, said lock barrel including a push button extending through said dial head bore, a head member rotatable in said lock barrel, means normally preventing rotation of said head member in said lock barrel, means normally preventing rotation of said lock barrel in said sleeve, key means operable to permit rotation of said head member in the lock barrel while the barrel remains stationary, said head member having an actuating member thereon extending through said closure and being adapted to engage a locking arm, and means to free the preventing means and permit rotation of the lock barrel in the sleeve when the dial tumblers are codified.

9. In a vehicle door handle assembly for a latch which includes a bolt, a locking member for the bolt, and an actuating member for moving the locking member to unlocked position, said handle assembly including a body having a chamber therein and having a bore communicating with the chamber, a lock barrel mounted to rotate and to reciprocate in the chamber, means to normally hold the lock barrel against rotation relative to the body while permitting reciprocation thereof, said lock barrel being operable to free the bolt when the lock barrel is moved axially while the locking member is in unlocked position, said actuating member being movable upon rotary movement of the lock barrel and adapted to move

the locking member to unlocked position, and tumbler controlled means operable when the tumbler controlled means is correctly positioned to free the holding means which normally holds the lock barrel against rotation relative to the body and to permit rotary movement of the lock barrel and movement of the actuating member to move the locking member to unlocked position.

10. In a vehicle door latch assembly which includes a bolt, a locking member for the bolt, and an actuating member for moving the locking member to unlocked position, said assembly including a body having a chamber therein and having a bore communicating with the chamber, a lock barrel mounted to rotate and to reciprocate in the chamber, means to normally hold the lock barrel against rotation relative to the body, said lock barrel being operable to free the bolt when the lock barrel is moved axially while the locking member is in unlocked position, said actuating member being movable when the lock barrel is rotated and adapted to move the locking member to unlocked position, and tumbler controlled means operable to free the holding means and to permit rotation of the lock barrel and actuating member.

11. In a vehicle door latch assembly which includes a bolt, a locking member for the bolt, and an actuating member for moving the locking member to unlocked position, a lock barrel mounted to rotate and to reciprocate, means normally holding the lock barrel against rotation while permitting reciprocation thereof, the lock barrel being operable to free the bolt when it is reciprocated while the locking member is in unlocked position and tumbler controlled means operable to free the holding means and to permit rotation of the lock barrel, said actuating member being rotatable when the lock barrel is rotated to move the locking member to unlocked position.
